CLAIM

The ornamental design of a mobility walker footing as shown and described.

DESCRIPTION

FIG. 1 is a front elevational view of a mobility walker footing in accordance with the present invention.

FIG. 2 is a rear elevational view thereof.

FIG. 3 is a bottom plan view thereof.

FIG. 4 is a top plan view thereof.

FIG. 5 is a left elevational view thereof.

FIG. 6 is a right elevational view thereof.

FIG. 7 is front perspective view thereof; and,

FIG. 8 is an exploded view thereof.

The broken lines are included for the purpose of illustrating portions of the mobility walker footing that form no part of the claimed design.

The mobility walker footing is not limited to the scale shown herein.

1 Claim, 7 Drawing Sheets
